VALVE TIP HARDENING MACHINE AND METHOD

Filed Sept. 12, 1931

UNITED STATES PATENT OFFICE

1,985,804

VALVE TIP HARDENING MACHINE AND
METHODWilliam H. Spire, Cleveland, Ohio, assignor to
Thompson Products, Incorporated, Cleveland,
Ohio, a corporation of Ohio

Application September 12, 1931, Serial No. 562,482

2 Claims. (Cl. 148—10)

This invention relates to means for, and the method of, heat treating the tips of the stems of poppet valves, such as are used in internal combustion engines.

- 5 The means, and the method, disclosed are not limited in their application to the heat treatment of valve stems, and many other applications of my invention will readily suggest themselves.
- 10 The tips of that end of a poppet valve stem that engages the valve operating mechanism of internal combustion engines is usually given a final heat treatment following the mechanical operations that give the valve its form.

- 15 The end of the stem is placed between a pair of opposed electrodes, current is sent through the tip of the stem to raise it to a desired temperature, and then the valve is placed in a quenching bath. It is obvious that the opposed jaws of the 20 clamping electrodes must be spaced apart to prevent their short-circuiting the path of the current through the clamped valved stem, and it follows that the current flowing from electrode to electrode through the stem will tend to follow 25 one short and relatively narrow path,—with consequent overheating of the metal in that path,—due to the magnetostriction of the current path. The electrodes do not clamp each succeeding specimen in precisely the same way; previous 30 mechanical treatment of the stem tip variously affects its conductivity to current, so to produce similar heating effect of the current in the same time would require extraordinary skill on the part of the operator of the machine, and tedious 35 adjustment of the current intensity.

- 40 It will be evident that when the major portion of the current, and of the heat energy, flows along a definite and relatively narrow path, the metal in that path will flow and adjust itself within the cross-section of the stem in a manner different from that of the colder metal bordering it, and that when the stem is quenched in the 45 hardening bath, the final condition of the periphery and of the internal structure of the cell cannot be satisfactory.

- I have heretofore sought to overcome the disadvantages mentioned by turning the stem on its longitudinal axis, but this necessitated repeatedly 50 opening and closing the clamping electrodes and the current supply, and was unsatisfactory because of the labor involved, the time consumed, the increased wear of the electrodes and switching mechanism, and the fact that the thermal and 55 electrical conductivity of each succeeding path was affected by what happened in previous applications of the current.

- It is an object of my invention to provide a machine for imparting heat treatment to the tips of valve stems so that a uniformly good 60 product may be obtained by an unskilled operator.

It is also an object of my invention to provide a method of heat treatment which is free of the disadvantages of prior methods.

Other and further important objects of my invention will appear in the description of my invention. 5

On the drawing:

Fig. 1 is a schematic diagram of the instrumentalities embodying my invention.

Figs. 2 and 3 are end views indicating heat flow 10 through the end of a heated valve stem during the operation of my machine.

In the drawing:

The numeral 10 indicates, generally, a conventional step-by-step switch mechanism, which 15 comprises a wiper arm 11 urged forward against a spring 12 by a pawl 13 engaging the teeth of a ratchet 15 and actuated by a magnet 14. The wiper arm successively makes contact with a plurality of spaced contacts 16. Retraction of the 20 wiper arm is prevented by a detent 17, and the arm is restored to its original position when the detent is raised by a releasing magnet 18.

The contacts 16 are extended, or are connected 25 to a row of contacts 19 so that a manually operated switch 20 may be moved to make connection with any of them.

When the machine is first put in service to treat a batch of valve spindles, the operator moves selector switch 20 to the zero position in contact 30 with the contact indicated by zero. The wiper arm should then be in its initial position.

The operator now closes a foot-switch 21, thereby causing current to flow from the alternating current supply mains along wire 22, 35 through switch 20, through wiper arm 11, along wire 23, through solenoid 24, of switch 25, and back to main wire 26. Current flowing through solenoid 24 moves switch 25 to close contacts 27, thereby providing a circuit from wire 22 through 40 solenoid 28, to retract a core 29 thereof, and thereby retract one of a pair of jaws of the electrodes 30, through a connecting link mechanism 31.

It is a simple matter to arrange things so that 45 both of the jaws are retracted at the same time, and this is usually done.

The tip portion of the stem of a valve 32 is now inserted between the electrodes 30, and the foot-switch 21 is now opened, whereupon the 50 jaws 30 close to clamp the valve under the urging of a spring 33, or similar means.

The jaws of the electrodes 30 are recessed, as indicated by numerals 34 on Figs. 2 and 3, so that the jaws may readily accommodate themselves 55 to the clamping of round stems of several different diameters, and also to define definite current paths through the cross-section of the stem adjacent opposed margins of the stem.

The operator now moves the selector switch to, 60

say, contact 3, and again closes the foot switch 21. There is now, at the outset, no current path through the selector switch, and switch 25 is in its normal position, closing contacts 35. Current now flows from wire 26, through solenoid 36 of switch 37, through contacts 38 of switch 39, through contacts 35 of switch 25, and back to wire 22. Current flowing through solenoid 36, closes switch 37, and thereby energizes the heating transformer 40 which is connected to the electrodes 30. When the current flows through the electrodes 30 and the tip of the stem of the valve 32, the tip becomes heated, and when the tip is viewed from above the two paths of greatest current intensity are clearly indicated by two transversely extending white regions with a duller region between, as indicated on Fig. 2.

Positioned above the heated stem is a photoelectric cell 41, of a conventional type, with a lens 42 to direct rays from the heated material to its light-sensitive electrode. The cell 41 is suitably connected to a power source through a conventional amplifier 43, to amplify the current flow of the cell. Connected to the cell 41 is a solenoid 44 of the switch 39, so that upon the current through the cell 41 attaining a predetermined intensity, indicating a predetermined temperature of the heated work, the solenoid 44 causes switch 39 to interrupt contacts 38, thereby de-energizing solenoid 36, and causing interruption of the heating current.

Solenoid 44 also causes switch 39 to close its contacts and thereby establish a circuit from a direct current source, through wire 46, contacts 45, magnet 14, and wire 47 to advance the wiper arm 11 one step forward.

When the supply circuit of transformer 40 is interrupted by this action of cell 41, the heat energy in the heated work diffuses uniformly over the cross-section of the material, and the whole end takes on the appearance of that of the intermediate strip of Fig. 2, as is indicated in Fig. 3. Immediately upon this uniform distribution of the heat energy taking place, the current through the cell 41 decreases slightly, and in consequence of this current decrease, switch 39 returns to its normal position to close contacts 38 and thereby close the circuit through solenoid 36 to close the transformer supply switch 37. The aforementioned cycle, changing the appearance of the heated end from that indicated in Fig. 2 to that indicated in Fig. 3, is repeated, with the wiper arm 11 advancing a step when the cell 41 breaks the heating current through switch 39.

When the wiper arm 11 has advanced to make contact with a contact that is connected to the selector switch 20, a circuit is again closed through wire 22, wire 23, solenoid 24, to wire 26, to move switch 25 to close contacts 27 and thereby energize solenoid 28 to retract an electrode jaw and drop the valve 32 into a hardening bath 48.

The operator now inserts another valve between the open jaws, and then momentarily releases the foot switch 21 to de-energize a solenoid 49, connected in parallel with wires 22 and 26, to release a switch 50, to close contacts 51, and thereby establish a circuit through the detent releasing magnet 16 and wires 46 and 47. The

wiper arm 11 returns to its original position, and now, without any effort of the operator other than to keep the foot switch 21 closed, the machine automatically gives the stem the desired number of heat cycles and then drops the valve into the hardening bath. 5

The proper number of cycles of alternate heating and heat flooding of the stem is determined, naturally, by the history of previous mechanical treatment given to it, but when a batch of formed valves is put through the machine they are usually inserted only a few seconds apart. 10

It is a simple matter to adjust the responsivity of the cell and of the associated amplifier and relays to obtain any reasonable variation in the 15 heat application and heat flooding periods to properly treat stems of different diameters and of different materials.

It will be understood that the conventional step-by-step mechanism described may be variously modified while retaining, in substance, its function in causing interruption of the heating current at the end of a predetermined number of heating cycles. 20

When a batch of material comprises stems or 25 rods which are substantially alike in their history of previous treatment, in diameter, and in composition, a given number of heating cycles usually takes place in a fairly definite period of time, so it would then be possible to arrange 30 things so that the heating current is interrupted and the jaws opened to drop the rod or stem at the end of a certain period following the closing of the foot switch.

I am aware that many changes may be made 35 and numerous details of construction may be varied through a wide range without departing from the principles of this invention, and I, therefore, do not purpose limiting the patent granted hereon otherwise than necessitated by the prior 40 art.

I claim:

1. The method of heat treating automotive engine valve stems of which the tip thereof is part of an electric heating circuit to produce cycles 45 of heating of high intensity and diffusion of heat in the tip during the heat treatment, which comprises the steps of applying timed and alternating applications of current of one intensity and then of another intensity through the metal in 50 rapid succession to produce periods of heating and of heat diffusion in the tip by means responsive to predetermined and alternating changes of temperature of the metal, and for a predetermined number of cycles. 55

2. In the heat treating of an automotive engine valve stem of which the tip thereof is part of an electric heating circuit to produce cycles of heating of high intensity and of heat diffusion in the tip, the method which comprises the steps 60 of conditioning the heating circuit to produce alternate applications of current of one intensity and then of another intensity in rapid succession through the tip by means responsive to predetermined and alternating changes in the temperature of the metal, and for a predetermined number of cycles. 65

WILLIAM H. SPINNE.
